G. H. WHEARY

WARDROBE TRUNK LOCK

Filed March 12, 1924

*Inventor,
George H. Wheary*

*By Frank M. Jones,
Attorney.*

UNITED STATES PATENT OFFICE.

GEORGE HENRY WHEARY, OF RACINE, WISCONSIN, ASSIGNOR TO WHEARY-BURGE TRUNK COMPANY, OF RACINE, WISCONSIN, A CORPORATION OF WISCONSIN.

WARDROBE-TRUNK LOCK.

Application filed March 12, 1924. Serial No. 698,666.

To all whom it may concern:

Be it known that I, GEORGE HENRY WHEARY, a citizen of the United States, and resident of Racine, in the county of Racine and State of Wisconsin, have invented new and useful Improvements in Wardrobe-Trunk Locks, of which the following is a description, reference being had to the accompanying drawing, which is a part of this specification.

This invention relates to certain new and useful improvements in wardrobe trunk locks and has a general object to provide a lock which will afford maximum strength and protection against tampering and unauthorized opening and which, at the same time, is of neat appearance.

It is another object of this invention to provide a lock of the character described in which stress on the lock proper is eliminated and distributed over a comparatively wide area to afford maximum strength.

Another object of this invention resides in the provision of a lock of the character described in which the pinion is concealed to thus further eliminate the possibility of tampering.

And a still further object of this invention resides in the provision of an interlocking connection between the hasp proper and the keeper to produce a cam action in the closing of the lock to draw the trunk sections together.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated two complete examples of the physical embodiment of my invention constructed according to the best modes I have so far devised for the practical application of the principles thereof, and in which:

Figure 1 is a perspective view of the upper portion of a wardrobe trunk equipped with my improved lock;

Figure 2 is a perspective view of the lock detached from the trunk with the hasp in an out-swung position;

Figure 3 is a view, partly in section and partly in elevation, taken transversely through Figure 2 on the plane of the line 3—3;

Figure 4 is a front plan view of a wardrobe trunk lock illustrating a slightly modified construction, and

Figure 5 is a transverse sectional view taken through Figure 4 on the plane of the line 5—5.

Referring now more particularly to the accompanying drawing, in which like numerals designate like parts throughout the several views; the numeral 5 designates the drawer section of a wardrobe trunk having the usual fixed top portion 6, and 7 the wardrobe section adapted to have its top closed by a movable top cover 8. The movable top cover 8 is hingedly connected to the fixed top 6 by a suitable fitting 9 and the outer end of the top 8 carries a hasp member 14 cooperating with a wardrobe section carried keeper to lock the trunk closed.

Secured to the outer end of top 8 by suitable fastening means 10 is a plate 11 provided with two spaced lugs or ears 12 between which a projection 13 on the upper end of a hasp member 14 is pivotally secured. The lugs 12 and projection 13 are bored to receive a pinion or pivot 14', which is concealed from view, as clearly illustrated in the drawing.

A keeper plate 15 is secured to the section 7, with its upper end abutting the lower end of the plate 11 when the trunk sections and the top 8 are closed, the plate 15 having its central portion provided with a recess or pocket 16 of a shape to conform with that of the hasp 14. Extended from opposite sides of the hasp, adjacent its hinged end, are laterally projecting lugs 17, the outer ends of which are directed inwardly, as at 18, to engage in slots 19 registering with pockets or offsets 20 communicating with the recess 16 and into which the projections 17 engage.

The other free end of the hasp carries a suitable lock mechanism 21, the barrel 22 of which extends through an aperture 23 communicating with the recess 16 when the hasp is positioned in the recess 16, the spring pressed bolts 24 of the lock mechanism engaging behind the peripheral edge 25 of the aperture.

As the trunk sections are closed and hasp

14 swung into place, the upper inner edges or corners 26 of the projection end 18 engage the upper ends 27 of the offsets 20, as clearly illustrated in Figure 3, and draw 5 the cover 8 tightly over the section 7 producing a cam action. As the hasp closes, the barrel 22 passes through the opening 23 and the spring bolts 24 engage behind the peripheral edge 25, as hereinbefore described.

An apertured lug or projection 27' is carried by the plate 16 to project through an opening 28 in the hasp to permit sealing of the lock, as illustrated in Figure 1.

15 That form of my invention illustrated in Figures 4 and 5 is substantially identical with that structure hereinbefore described with the exception that in place of the lateral projections 17, the sides of the hasp are recessed, as at 29, and the sides of the recess 16 provided with inward extensions 30 to provide the desired interlocking connection. The hasp is flush with the keeper when closed in both forms of my invention.

20 25 From the foregoing description taken in connection with the accompanying drawing, it will be readily obvious to those skilled in the art to which an invention of this character appertains that I provide a locking device which, while illustrated in connection with a wardrobe trunk, may be used in other places, which will afford protection against tampering and unauthorized opening, is of strong construction and which 35 is of neat appearance and will in no wise mar the trunk or other device to which it is attached.

What I claim as my invention is:

1. A device of the character described, 40 comprising a hasp, means pivotally mounting the hasp, a keeper plate having a recess in its front face to conform with the shape of and receive the hasp with its outer surface flush with the outer surface of the 45 keeper plate, means for securing the hasp in the keeper plate recess, and interlocking

projections carried by either the keeper plate or hasp for relieving the strain on the means for securing the hasp in the keeper recess, said projections being substantially flush with the outer surface of the keeper plate and hasp when the plate and hasp are engaged.

2. A device of the character described, 45 comprising a hasp member, means pivotally mounting the hasp member, a keeper member having its front face recessed to provide a pocket in which the hasp member is engageable with its front face substantially flush with the front face of the keeper member, a lock mechanism for securing the hasp member in the keeper plate pocket, and transverse projections extended from one member and substantially flush therewith, said other member having transverse 50 recesses in which the transverse projections are movable and the projections producing a cam action to draw the hasp member mounting and the keeper member together as the projections are engaged.

3. A device of the character described, 55 comprising a hasp, a hasp mounting plate, means pivotally securing the hasp to the mounting plate, a keeper plate having a recess in its front face to receive and conform 60 with the shape of the hasp, and said hasp, when positioned in the recess, having its outer surface flush with the outer surface of the keeper plate, means for securing the hasp in the keeper plate recess, a projection 65 extending laterally from the side of the hasp, and an inwardly extended end on the projection adapted to engage within a slot in the keeper plate adjacent the recess therein, said inwardly extending end engaging in said slot and drawing its mounting plate and the keeper plate together as the hasp is swung in the said keeper plate recess.

In testimony whereof I affix my signature.

GEORGE HENRY WHEARY.
